UNITED STATES PATENT OFFICE.

THOMAS E. MURRAY, OF NEW YORK, N. Y.

DESIGN FOR AN ELECTRIC CUT-OUT HOLDER.

No. 39,435.

Specification for Design.

Patented July 28, 1908.

Application filed March 19, 1908. Serial No. 422,192. Term of patent 7 years.

To all whom it may concern:

Be it known that I, THOMAS E. MURRAY, a citizen of the United States, residing at New York, in the county of New York and State of New York, have invented an original and ornamental Design for an Electric Cut-Out Holder, of which the following is a specification, reference being had to the accompanying drawing forming a part hereof.

The figure is a perspective view of an electric cut-out holder, showing my new design.

I claim:

The ornamental design for an electric cut out holder, as shown.

THOMAS E. MURRAY.
